UNITED STATES PATENT OFFICE.

MICHAEL R. BIRMINGHAM, OF YONKERS, NEW YORK.

ATTACHMENT FOR PILE-FABRIC LOOMS.

Application filed October 25, 1921. Serial No. 510,284.

To all whom it may concern:

Be it known that I, MICHAEL R. BIRMINGHAM, a citizen of the United States, and a resident of Yonkers, county of Westchester, 5 and State of New York, have invented certain new and useful Improvements in Attachments for Pile-Fabric Looms, of which the following is a specification.

This invention relates to improvements in 10 attachments for pile fabric looms and especially to a device for holding the free ends of the pile wires in position during the weaving operation before they are securely seized by the weave of the fabric.

15 The object of the invention is to provide a simple, inexpensive and effective device which may be applied to looms of this general character and which will render the operation of the loom more certain. More 20 specifically its object is to provide a simple device for holding the pile wires in desired position and in proper spaced relation during the part of their cycle of operation in which their ends are usually left free, and 25 during which time they are liable to turn over or become bent or unevenly spaced. This and other objects of the invention will appear in the following specification in which I will describe the invention and the 30 novel features of which I will set forth in the appended claims.

Referring to the drawings, Fig. 1 is a plan view of a portion of a pile fabric loom with a device attached thereto which embodies my invention.

Fig. 2 is a side elevation of a preferred form of my new device with some pile wires thereon shown in section.

Fig. 3 is a plan view of the device.

40 Fig. 4 is a front elevation of the same mechanism.

Fig. 5 is a side elevation on an enlarged scale of a toothed wheel which forms a part of the device together with certain cooperating parts shown in outline for the purpose of illustrating the operation.

Like characters of reference designate corresponding parts in all the figures of the drawings.

50 10 designates a part of the frame of a loom in which a fabric 11 is being formed. 12 designates the longitudinal fibers of this

fabric and 13 a shuttle which carries the transverse fiber. 14 is a pile wire, several of which are shown in position in Fig. 1. Each 55 of these carries a knife or cutting edge near its free end. A reed 16 has upwardly projecting reed posts 17 which engage the pile wires and force them forwardly. This forward movement of the pile wires is also assisted by an auxiliary bracket 18 that engages the wires on the outer side of the clamp and prevents strain on the wires as they pass through the clamp. It is essential that this knife edge be held in correct cutting 60 position so that when the pile wires are withdrawn the fibers will be severed properly to give the pile effect to the fabric.

For this purpose I provide a device for receiving and holding the pile wires near 70 their free ends. This device, designated generally by the reference numeral 20, comprises a plate 21 which is secured to the frame of the loom as by a bolt at 22, an arm 23, the end of which adjacent the plate 75 is slotted as at 24 and fitted to slide longitudinally under a lug 25 which is a part of the plate. 26 is a headed pivot secured to the plate and passing through the slot in arm 23. This provides a structure for adjusting the 80 device to the loom whereby it may be held in operative position. Also by sliding arm 23 forwardly in the plate as far as the length of the slot will permit, the arm may be swung out of the way into the position in 85 which it is indicated at 23^a in Fig. 1.

The forward end of the arm 23 forms a track or platform 27 for receiving the pile wires. A projection 28 from one side of this platform affords a ready grip for swinging 90 the arm aside, and a projection 29 from the opposite side is provided to form a support under the selvage for the pile wires, to hold the wires when the wires are first inserted after a heading has been formed. 95 The term "heading" is used in the art by weavers to indicate that part of a carpet or rug formed at each end thereof and woven without pile and this portion of the carpet or rug is cut upon the completion of the 100 article.

A bow spring 30 is affixed to the arm 23 at 31 and this extends forwardly over the platform 27. A head 32 is secured to the

forward end of this bow spring as by being dove-tailed to fit the end of the spring as shown at 33, and bolted to the spring at 34. The head is constructed to form a downwardly curved cam surface 35, an oppositely inclined surface 36 and a vertical shoulder 37.

In the head is rotatably supported a toothed wheel 40, the teeth of which are 10 formed to cooperate with the surfaces of the platform, of the head and with the pile wires. This may be freely rotative or a ratchet spring 41 may be provided to position the teeth of the wheel and to prevent the 15 rotation of the wheel in one direction. The platform 27 is recessed or depressed at 42 to clear this wheel, thereby providing the platform with a portion 43 disposed in a plane above the recessed portion to assist in retaining one wire when the next succeeding 20 wire is being received between the wheel teeth.

A rigid guide 50 is affixed to the arm 23 at 51 and this has an edge 52 parallel with 25 the platform 27 and spaced therefrom a distance equal to the height of the pile wires.

The operation of this device will be described, by reference to Figs. 2 and 5. The 30 pile wires 14 are advanced one at a time by the loom reed assisted by bracket 18, from right to left. When one of them reaches the position 14^a on the platform 27 it comes in contact with the cam surface 35. Its 35 further movement to the left raises the head 32 against the pressure exerted by the bow spring. As soon as the pile wire reaches a position under the surface 36 of the head it rises on the incline to the higher portion 40 43 of the platform into the position in which it is shown at 14^b (Fig. 5), into the space between two of the teeth of the wheel 40. The pile wire will be held securely in this position by the cooperation of the teeth 45 of the wheel 40 and the vertical shoulder 27 of the head 32. The teeth are constructed to form parallel sides which in this position stand vertically.

When the next pile wire is moved past 50 position 14^a it will raise the head 32 and the wheel 40 but the surface 52 of the rigid guide 50 will hold the wire shown at position 14^b down on the platform 27 while this wire now embedded in the fabric is moved 55 by the action of the loom reed to the position 14^c. The shape of the wheel teeth is such as to still hold this wire up and spaced an exact distance from the wire at 14^b. The approach of the next pile wire will move 60 one of the wires from 14^c to 14^a where it is released from the wheel. But at such a time it is firmly supported in proper position in the fabric itself and needs no other support.

65 When the ratchet spring 41 is used it not

only positions the wheel but prevents its rotation in one direction.

This invention may be used with other structures than the specific one shown as an illustration and I intend no limitations 70 other than those imposed by the appended claims.

What I claim is:

1. The combination with a pile wire supporting platform, a head, a bow spring supporting the head in definite relation to the platform and permitting movement of the head from and toward the platform, said head having a shoulder arranged to engage a pile wire near the free end thereof and to 80 coact with the platform to hold the wire in a definite position and arranged to be raised by the advance of a pile wire to release the held wire.

2. The combination with a pile wire supporting platform, a head, and a bow spring supporting the head in definite relation to the platform and permitting movement of the head from and toward the platform, said head having a shoulder arranged to engage a pile wire near the free end thereof and to coact with the platform to hold the wire in a definite position, said head having 90 oppositely inclined under surfaces arranged to be engaged by and to engage the pile 95 wire.

3. The combination with a pile wire supporting platform, a head, and a bow spring supporting the head in definite relation to the platform and permitting movement of the head from and toward the platform, said head having a shoulder arranged to engage a pile wire near the free end thereof and to coact with the platform to hold the wire in a definite position, said head having 100 a cam surface arranged to be engaged by a pile wire extending downwardly and rearwardly, terminating short of the shoulder, and an oppositely inclined surface joining the shoulder and the cam.

4. The combination with a pile wire supporting platform, a head, a bow spring supporting the head in definite relation to the platform and permitting movement of the head from and toward the platform, said head having a shoulder arranged to engage a pile wire near the free end thereof and to coact with the platform to hold the wire in a definite position, means for lifting the head to 115 release the held wire comprising a pile wire movable between the platform preventing underlying pile wires from rising as the head is lifted.

5. The combination with a pile wire supporting platform, a head, and a bow spring 125 supporting the head in definite relation to the platform and permitting movement of the head from and toward the platform, said head having a shoulder arranged to engage a pile wire near the free end thereof and to 130

coact with the platform to hold the wire in a definite position, said head having a cam surface arranged to be engaged by a pile wire extending downwardly and rearwardly, 5 terminating short of the shoulder, an oppositely inclined surface joining the shoulder and the cam, and a fixed guide at one side of the head in spaced relation to the platform preventing underlying pile wires 10 from rising as the head is lifted.

6. The combination with a pile wire supporting platform, a head, a resilient connection between the platform and head permitting movement of the head 15 away from and toward the platform, said head having a shoulder arranged to engage a pile wire near the free end thereof, a toothed wheel having spaces between its teeth for receiving the pile wire, and means for elevating the head and 20 rotating the wheel to release the held wire, comprising a pile wire movable between the platform and the head.

7. The combination with a pile wire supporting platform, a head, a resilient connection between the platform and head permitting movement of the head away from and toward the platform, said head having a shoulder arranged to engage a pile wire 30 near the free end thereof, a toothed wheel having spaces between its teeth for receiving the pile wire, and means for elevating the head and rotating the wheel to release the held wire, comprising a pile wire movable between the platform and the head, the teeth of said wheel being arranged to space the released wire from the held wire.

8. The combination with a pile wire supporting platform, a head, a resilient connection between the platform and head, permitting movement of the head away from and toward the platform, said head having a shoulder arranged to engage a pile wire near the free end thereof, a toothed wheel 45 having spaces between its teeth for receiving the pile wire, means for elevating the head and rotating the wheel to release the held wire, comprising a pile wire movable between the platform and the head, the teeth of said wheel being arranged to space the released wire from the held wire, and a fixed guide in spaced relation to the platform preventing underlying pile wires from rising when the platform is elevated.

55 9. The combination with a pile wire supporting platform, a head, a resilient connection between the platform and head permitting movement of the head away from and toward the platform, said head having 60 a shoulder arranged to engage a pile wire near the free end thereof, a toothed wheel having spaces between its teeth for receiving the pile wire, a ratchet engaging said wheel to prevent its rotation in one direction, and means for elevating the head and

rotating the wheel to release the held wire, comprising a pile wire movable between the platform and the head, the teeth of said wheel being arranged to space the released wire from the held wire.

10. The combination with a pile wire supporting platform, a head, a resilient connection between the platform and head permitting movement of the head away from and toward the platform, said head having a shoulder arranged to engage a pile wire near the free end thereof, a toothed wheel having spaces between its teeth for receiving the pile wire, said platform being depressed to receive the lowermost part of the wheel, a spring engaging the teeth of said wheel arranged to position the wheel and to prevent its rotation in one direction, means for elevating the head and rotating the wheel to release the held wire, comprising a pile wire movable between the platform and the head, and a fixed guide in spaced relation to the platform preventing underlying pile wires from rising when the platform is elevated.

11. The combination with a loom frame, a bracket affixed thereto, a pile wire supporting platform swingably connected with the bracket, means for holding the platform against swinging, said platform having a lateral projection, a head, a bow spring supporting the head in definite relation to the platform and permitting movement of the head from and toward the platform, said head having a shoulder arranged to engage a pile wire near the free end thereof and to coact with the platform to hold the wire in a definite position and arranged to be raised by the advance of a pile wire to release the held wire.

12. The combination with a loom frame, a bracket affixed thereto, a pile wire supporting platform swingably connected with the bracket, means for holding the platform against swinging, said platform having a lateral projection, a head, a bow spring between the track and head permitting movement of the head away from and toward the platform, said head having a shoulder arranged to engage a pile wire near the free end thereof, a toothed wheel having spaces between its teeth for receiving the pile wire, means for elevating the head and rotating the wheel to release the held wire, comprising a pile wire movable between the platform and the head, and a fixed guide in spaced relation to the platform preventing underlying pile wires from rising when the platform is elevated.

13. The combination with a loom frame, a bracket affixed thereto, a pile wire supporting platform swingably connected with the bracket, said platform having a lateral projection, a head, a resilient support therefor permitting movement of the head away

from and toward the platform, and a toothed wheel rotatively supported on the head arranged to engage a pile wire.

14. The combination with a loom frame, a bracket affixed thereto, a pile wire supporting platform swingably connected with the bracket, said platform having a lateral projection, a head, a resilient support therefor permitting movement of the head away from and toward the platform, a toothed wheel rotatively supported on the head arranged to engage a pile wire, and a fixed guide at one side of the head in spaced relation to the platform preventing underlying pile wires from rising as the head is lifted.

15. The combination with a loom frame, a bracket affixed thereto, a pile wire supporting platform carried by the bracket having a depressed portion and an elevated portion, and a toothed wheel movably supported above the platform and adapted to receive and position the pile wires.

16. The combination with a loom frame, a bracket affixed thereto, a platform carried by

the bracket having a depressed portion and an elevated portion, and a toothed wheel movably supported above the platform and adapted to receive pile wires on the lower level of the platform and force them on the upper level whereby one pile is retained by the wheel as the next succeeding pile is moving toward the wheel.

17. The combination with a loom frame, a bracket affixed thereto, a pile wire supporting platform connected with the bracket and having a depressed and an elevated portion, a head, a resilient support therefor permitting movement of the head away from and toward the platform, and a toothed wheel rotatively supported on the head arranged to engage a pile wire, the elevated portion of the platform retaining one pile wire in the wheel as the head is raised by the next succeeding pile wire.

In witness whereof, I have hereunto set my hand this 14th day of October, 1921.

MICHAEL R. BIRMINGHAM.
